UNITED STATES PATENT OFFICE.

JEFFRIES ROBERT BRANDEN, OF DETROIT, MICHIGAN.

ALARM.

SPECIFICATION forming part of Letters Patent No. 354,884, dated December 28, 1886.

Application filed August 18, 1885. Serial No. 174,717. (No model.)

To all whom it may concern:

Be it known that I, JEFFRIES ROBERT BRANDEN, of Detroit, in the county of Wayne and State of Michigan, have invented certain new and useful Improvements in Alarms; and I do hereby declare that the following is a full, clear, and exact description of the invention, which will enable others skilled in the art to which it appertains to make and use the same, reference being had to the accompanying drawings, and to the letters of reference marked thereon, which form part of this specification.

The object of this invention is to provide novel and efficient mechanism for sounding an alarm in case of burglary or for calling the police or outside aid.

In the drawings, Figure 1 is a side elevation of the apparatus. Fig. 2 is a plan view of same, partly in section. Fig. 3 is a side elevation in which the cylinder is replaced by a bellows. Fig. 4 is a plan view of the device as shown in Fig. 3, and Fig. 5 is a detail view of certain parts.

In Figs. 1 and 2 is represented an air-pump consisting of an air-cylinder, *a*, an air-valve chest, *A*, provided with the valve-ports *D D'* *E E'*, which alternately receive and discharge air, as will be understood from the explanation of the construction and operation herein-after, and piston *b*. (See partial section, Fig. 2.)

The latter receives a reciprocating motion from the piston *c* and the crank *d*. This crank is actuated by a clock-work mechanism composed of the shafts *e e' e''*, the gear-wheels *f f' f'' f'''*, the bearings *g g' g'' g'''*, and the drum *h*, upon which is wound a string, *i*, having attached to it a weight, *k*, which may be conveniently replaced by a spring causing the same action.

In one side of the drum *h* are suitably fastened pins *l*, for the purpose hereinafter stated.

M is an air chamber or accumulator, connected with the air-valve chest *A* by means of a pipe, *N*. The air-chamber *M* is also provided with a valve mechanism, *o*, (shown also in detail, Fig. 5,) and of which mention will be made hereinafter. *p* is a pipe leading from the valve to the whistle *q*.

In Figs. 3 and 4 all parts are the same as in Figs. 1 and 2, excepting that the air-pump consists of the bellows *r*, the guides *s*, and the connecting-rod *t*, instead of the cylinder, piston, and piston-rod, as heretofore described.

Fig. 5 represents the valve mechanism illustrated on a larger scale. It consists of a plate, *u*, which closes or opens the opening *v* of the accumulator, and of the pivoted lever *w*, actuated by the pins *l* and the spring *x*. *Y* in Figs. 1 and 3 is a pivoted anchor having a projecting hook, *a'*, which hooks onto the pins *L* on the wheel *f'*, and to which anchor is attached the strings *z z'*, for reasons to be given.

The operation of the apparatus is as follows: When the anchor *Y* is pulled off from the pins *L L* by the string *z*, the clock-work mechanism is set in motion by the weight *k*, (or by a spring, as the case may be,) causing the crank *d* to rotate and impart to the piston a reciprocating motion, the cylinder meanwhile oscillating in the bearings *g g'*, in which it is trunnioned, in front of the air-valve chest *A*, drawing air in through the ports *D D'* and discharging it through the ports *E E'* alternately, and the connecting-pipe *N* into the air chamber or accumulator *M*, causing therein a suitable pressure of air, which is forced through opening *v* and the hose or pipe *p* into the whistle *q*, causing it to sound. The opening and closing of the opening *v*, which is effected by plate *u*, the pivoted lever *w*, the spring *x*, and the pins *l* on the revolving drum *h*, will cause the whistle to sound successive blasts, conforming to the usual police-calls.

The strings *z z'* may be attached to doors or windows of premises, and thus be made to act automatically, or may be hung in any convenient place to be pulled by the hand. The string *z'* is for the purpose of stopping the mechanism when the action of the apparatus has lasted long enough. The same result is brought about by the bellows *r*, Figs. 3 and 4, in place of the cylinder *a* and the piston *b* in Figs. 1 and 2, the one end of the bellows being stationary, while the other receives a reciprocating motion from the crank *d*, substantially the same as the piston *b* in Figs. 1 and 2, and the air is drawn into the bellows through the valve *G* and forced into the air chamber or accumulator through the valve *G'* and the pipe *N'*. The piston *b* and the piston-rod *c* in Figs. 1 and 2 are not packed in tightly, but allow a trifling leakage, for the reason that it causes no friction, and at the same time serves another purpose, viz: When the opening *v* is closed the action of the air-tight piston and

piston-rod would eventually cause so much pressure in the accumulator that it could not be overcome by the weight *k*, (or its substitute—a spring,) and would thus stop the entire

5 mechanism, while a slightly-leaking piston and piston-rod would overcome this defect. For the same reason the valve *G* in Fig. 3 in the bellows *r* is allowed a trifling leakage.

What I claim as my invention is—

10 1. An alarm and police call consisting of the accumulator *M*, provided with a flexible tube having a whistle attached thereto, and an opening, *v*, the air-compressing cylinder, the piston of which is connected to clock mechanism having drum *h*, provided with side pins, *l*, in combination with the pivoted lever *w* and slide-valve *u*, as set forth.

15 2. The combination, with cylinder *a*, trunnioned and provided with alternate receiving and discharging air-ports *D D' E E'*, pipe *N*, accumulator *M*, having opening *v*, and whistle *g*, slide-valve *u*, lever *w*, and piston *b*, of a

motor having a drum provided with lever-operating side pins, and a crank-shaft geared with the drum for reciprocating the piston, as 25 set forth.

3. In combination, a motor having a drum provided with pins *l l*, wheel *f'*, having pins *L L*, a pivoted bell-crank stopping-lever, *Y*, having cords *z z'* secured to its outer ends, and 30 a projecting hook, *a'*, pivoted lever *w*, and valve *u*, loosely connected thereto, the crank *d*, piston-rod *c*, having-piston-head *b*, the pipe-connection *N*, the accumulator *M*, and the flexible pipe *h*, having whistle *g*, substantially 35 as set forth.

In testimony that I claim the foregoing as my own I affix my signature in presence of two witnesses.

JEFFRIES ROBERT BRANDEN.
